(57) **CLAIM**

The ornamental design for a pure water sampling device as shown and described.

DESCRIPTION

FIG. 1 is a front view of a pure water sampling device, of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top plan and right side perspective view thereof;

FIG. 8 is a rear, bottom plan and left side perspective view thereof;

FIG. 9 is a reference reduced front view showing the state of use thereof;

FIG. 10 is a reference reduced right side view showing the state of use thereof;

FIG. 11 is another reference reduced front view showing the state of use thereof; and,

FIG. 12 is another reference reduced right side view showing the state of use thereof.

The features shown in evenly-dashed broken lines depict environmental subject matter only and form no part of the claimed design.
